UNITED STATES PATENT OFFICE

JOHN QUAGLIA, OF NEW YORK, N. Y.

DESIGN FOR A STREET-POST LAMP SIGN

Application filed December 7, 1929. Serial No. 33,683. Term of patent 7 years.

To all whom it may concern:

Be it known that I, JOHN QUAGLIA, a subject of the Crown of Italy, but having declared my intention to become a citizen of the United States, residing at New York, in the county of New York, State of New York, have invented a new, original, and ornamental Design for a Street-Post Lamp Sign, of which the following is a specification, reference being had to the accompanying drawing, forming part thereof.

In the drawings:

Figure 1 is a top plan view, and Figure 2 is a side elevation.

I claim:

The ornamental design for a street post lamp sign as shown.

JOHN QUAGLIA.
